ATTY'S.

UNITED STATES PATENT OFFICE.

FRANK F. B. CHAPMAN, OF WINCHESTER, MASSACHUSETTS.

COLLAPSIBLE TUBE.

1,242,654.

Specification of Letters Patent.

Patented Oct. 9, 1917.

Application filed February 24, 1917. Serial No. 150,684.

To all whom it may concern:

Be it known that I, FRANK F. B. CHAPMAN, a citizen of the United States, residing at Winchester, in the county of Middlesex and State of Massachusetts, have invented new and useful Improvements in Collapsible Tubes, of which the following is a specification.

This invention relates to a tube for holding and dispensing liquid materials, the tube being provided with a collapsible body, made of thin sheet metal or metallic alloy, and a rigid head forming one end of the tube and including a rigid neck constituting an outlet through which liquid is forced when collapsing pressure is exerted on the body of the tube.

The invention has for its object to provide a tube of this character adapted to contain thin, freely flowing liquids, such as liquid bluing, for laundry use, to insure a slow and regulated discharge of the liquid and to prevent leakage and evaporation of the liquid when the same is not under pressure, without depending on an external cap or closure to prevent such leakage and evaporation.

The invention is embodied in the improvements which I will now proceed to describe and claim.

Of the accompanying drawings forming a part of this specification,—

Figure 1 is a sectional view of a portion of a collapsible tube embodying the invention.

Fig. 2 is a section on line 2—2 of Fig. 1, showing the diaphragm hereinafter described, in its normal position.

Fig. 3 is a section on line 3—3 of Fig. 2.

Fig. 4 is a sectional view similar to Fig. 2, showing the diaphragm distended.

Fig. 5 is a section on line 5—5 of Fig. 4.

Figs. 6 and 7 are views similar to Fig. 3, showing different forms of liquid-tight joints.

The same reference characters indicate the same or similar parts in all of the figures.

The body 12 of my improved tube is of the usual collapsible construction, and is provided at one end with a rigid head, which includes a rigid breast portion 13 and a rigid tubular neck 14, the bore of which constitutes an outlet through which the contents of the tube are ejected, the body 12 being a thin-walled cylinder composed of a

suitable ductile metal or alloy, and adapted to be filled at its lower end, said end being closed in the usual manner after the tube has been filled.

15 represents a flexible diaphragm, composed of a thin circular sheet of elastic rubber, having a vent 16 formed by penetrating the diaphragm, without removing any of the material thereof. When the diaphragm is in a flat condition the vent 16 is contracted and closed, so that the liquid contents of the tube, when not under pressure, cannot pass through the vent.

The area of the diaphragm is greater than the cross-sectional area of the bore of the neck 14, and its margin is positively secured to the rigid head, in such manner as to form a liquid-tight joint between the margin of the diaphragm and the head, so that the only outlet for the liquid is through the vent.

In the embodiment of the invention shown by Figs. 1 to 5, the said liquid-tight joint is created by forming an annular recess 17, in the inner end of the neck portion of the head, one end of said recess forming a shoulder, or seat 18 surrounding the bore of the neck 14, and inserting the marginal portion of the diaphragm and confining means such as a clamping-ring 19 in said recess, the said marginal portion being bent over the ring and clamped between one edge of the ring and the seat 18.

The positive connection thus provided between the margin of the diaphragm and the head not only forms a liquid-tight joint, but also maintains the diaphragm in a flat condition, as shown by Figs. 1, 2 and 3, although not under tension, the marginal confinement of the diaphragm preventing sideways displacement of the central portion of the diaphragm by the charge of liquid, when the latter is not under pressure, so that if the tube were inverted or laid on its side, there would be no leakage through the vent 16. When, however, the body of the tube is compressed and pressure is exerted on the contained liquid, the pressure bulges the diaphragm outward and distends the vent 16, as indicated by Figs. 4 and 5, so that there is a limited flow of liquid through the vent. The flow is regulated by the vent which prevents an excessive or undesirably rapid flow, a result which is very desirable in dispensing liquid bluing, a small quantity

of which is sufficient to tint a large body of water.

The location of the diaphragm at the inner end portion of the neck 14 enables the neck to serve as a guard for the diaphragm, preventing liability of the accidental inward flexure of the diaphragm and the opening of the vent by contact with an external object should the tube be laid on its side while the outer end of the neck is open or uncovered.

The neck may be provided with a suitable cap or cover 21, the chief function of which is to close the neck while the tube is in storage, and before it is used. The cap may be permanently discarded when the tube is ready for use.

In the modification shown by Fig. 6, the neck is reduced and its outer end forms an external seat 22, between which and a flanged clamping-ring 23 the bent marginal portion of the diaphragm 15 is clamped.

It is obvious that the diaphragm may be provided with more than one vent, if desired.

The liquid-tight joint may be formed by uniting the marginal portion of the diaphragm to the breast portion of the head by confining means provided by a layer 25 of glue or cement, as shown by Fig. 7. The material of the layer 25 should be insoluble in the liquid contained in the tube, and adapted to adhere firmly both to the metal of the head, and to the rubber diaphragm.

The portion of the breast with which the layer, or annular connection 25 contacts, constitutes an annular seat, to which the

marginal portion of the diaphragm is united by said confining means.

In each embodiment of the invention shown by the drawings, the diaphragm is maintained normally flat by marginal confining means forming a liquid-tight joint at the margin of the diaphragm, the diaphragm forming a closure adapted normally to seal the tube against the escape of liquid, and permitting a regulated discharge of liquid only through the vent when collapsing pressure is exerted on the tube.

I claim:

A collapsible tube having a rigid head including a tubular neck constituting the outlet of the tube, a continuous annular seat surrounding said outlet, a flexible diaphragm having an area exceeding the cross-sectional area of said outlet, and confining means positively securing the marginal portion of the diaphragm to said seat to form a liquid-tight joint surrounding the outlet, and maintaining the diaphragm normally flat, said diaphragm having a vent which is formed by penetrating the diaphragm without removing material therefrom, whereby the vent is closed when the diaphragm is flat, said diaphragm constituting a closure adapted normally to seal the tube against the escape of liquid, and permitting a regulated discharge of liquid only through said vent when collapsing pressure is exerted on the tube.

In testimony whereof I have affixed my signature.

FRANK F. B. CHAPMAN.
